PICTURE TELEGRAPHY

Application filed April 14, 1927, Serial No. 183,631, and in Great Britain April 21, 1926.

This invention relates to picture telegraphy, and more particularly to what is sometimes termed "message" picture telegraphy.

It is desirable that apparatus for picture telegraphy should be able to fulfill the following requirements:

1. It should be able to transmit a message or picture immediately without it being necessary to prepare a special form, either photographically or in any other way.

2. It should be able to transmit a message or picture which has been written or drawn upon ordinary paper or the like.

3. It should be able to transmit a message or picture while the message form itself is stationary or moving only slowly. It will be seen that the positioning of a message form upon a rapidly moving part of the apparatus is likely to involve considerable difficulty, while if the apparatus has to be stopped, for the message form to be placed in position, delay will result.

4. If the apparatus includes a source of light and a photo-electric cell or the like (as apparatus for picture telegraphy almost invariably does), these should be stationary.

5. In the case of a receiver, in addition to the above requirements, it is desirable that there should be some simple indication that the picture is registering properly on the sensitive form used for reception.

According to the present invention, apparatus for the telegraphic transmission and reception of pictures or the like comprises a stationary source of light, an optical system for projecting a point of light upon a message form or upon a message receiving device, and means for moving the optical system, whereby the point of light is caused to move over substantially the whole surface of the message form or message receiving device.

The invention is illustrated in the accompanying drawings in which Figures 1 and 2 show in schematic form two modifications in accordance therewith, while Figure 3 shows in elevation, and Figure 4 in plan, a further modification. Throughout the figures, like parts are designated by like reference numerals.

50 Referring first to Figure 1, 1.1 are lines rep-

resenting the boundaries of a beam of light from an arc or other suitable source. The said light is projected axially along a tube 2, and after passing through suitable condenser arrangements (not shown), is diverted by means of a right angle prism 3 through a right angle. It then passes through a focusing lens 4 in the wall of the tube 2, and is focussed to form an image point at 5 upon the message from 6 which is suitably affixed to the outside of a carrier 7 formed as a tube or part of a tube concentric with the first mentioned tube, and made of transparent material, such as glass.

Light is reflected back from the image point 5 through a suitable lens arrangement 8 carried by the tube 2 on to a mirror 9 placed transversally across the said tube, whence the reflected beam is diverted through a right angle so that it is projected axially along the tube in the same direction in which the light from the original source was projected. This reflected light is then focussed upon a photo-electric cell, as illustrated diagrammatically and conventionally by the numeral 35. Any well known means are provided for rotating or oscillating the tube and also for progressively advancing the said tube in an axial direction, so that the image point upon the message form moves over substantially the whole surface of the said message form. The lens 8, through which the light reflected from the image point passes, is concentric with and larger than the focussing lens 4, the latter being arranged in a protecting tube 10 passing through the former and embracing the prism so that there is no interference between the outgoing and the reflected light. 11 is a mirror for collecting the reflected light reflected from the form or device 6.

It will be seen that the light reflected from the message form will vary in intensity and strength with the message inscribed upon the said form, since the amount of reflected light will vary with the degree of light and shade of the message upon the said message form.

In a modification, the tube is oscillated or rotated, while the message carrier is progressively advanced in an axial direction. Preferably the means for causing relative axial pro-

gression between the tube and the message carrier comprises a clutching device, whereby the said mechanism may be disengaged while the message form is placed in position.

Instead of using a transparent glass cylinder for the support of the message, we may alternatively use a brass or other metal supporting surface. In such a case a slot is cut in the cylinder in order to allow the light to fall on the message surface. The relative motion between message and the rotating tube is then obtained by sliding the message over the surface of the brass cylinder. By this means every part of the message successively passes

15 the slot.

In a further modification, illustrated in Figure 2, the lens 8 through which the reflected light passes is located further along the tube than the focussing lens 4, there being 20 provided a spherical mirror 11 whose centre is the focus point, the said mirror serving to collect the reflected light for projection through the said lens 8.

The arrangements hereinbefore described 25 may be rendered suitable for the reception of picture telegraphy by substituting for the message form and associated optical system for collecting the reflected light, a Kerr cell or other light modulating device, and a light 30 sensitive receiving surface. The light from the arc lamp or other source is modulated by the Kerr cell and focussed by the prism and lens upon the sensitive receiving surface.

It will be seen that in a receiving arrangement in accordance with this invention, owing to the persistence of vision, it is possible to ascertain whether the received message is registering properly on the form since each line traced by the focus point will be 40 seen by the eye as a streak across the receiving surface, and it can at once be seen whether this streak is falling in the correct place on the form. The arrangement of apparatus illustrated by Figs. 3 and 4 is intended to

45 function in a manner identical to that conventionally shown by the diagrams of Figs. 1 and 2 and, to refer to Fig. 3 the screwed shaft 18 which is driven from the worm 18 of Fig. 4 is arranged at all times to carry a 50 message form 6 longitudinally of the light systems 20 and 21 so that light, as directed through the tube 2 in the manner shown in Figs. 1 and 2, will strike the light system 20 (corresponding to 3 of Figs. 1 and 2) and be 55 projected through the slot 30 against the message form 6 from which it is redirected as reflected light through the lens system 8 in the same manner as shown in Fig. 2 and brought to act upon the rotating reflecting system 21 60 (corresponding to 9 of Fig. 2). The motion of the message form 6 is continuous and is derived as above stated from the rotation of the motor 12 so that as the light system is rotated from the worm connection 19, new

65 portions of the picture to be transmitted will

be placed continuously above the slotted portion 30 of the message form 6 so as to enable the light beam entering the reflecting lens system 20 from a point to the right of 20 (looking at Fig. 4) to scan all portions of the 70 picture carried by the message form. As shown in Fig. 3 there is a large bracket arm 31 carried from a pivotal mounting 32. The bracket arm or yoke 31 is preferably provided with any suitable form of belt of a desired width for holding the message tight against the message form 6, and the pivotal connection provides means whereby the bracket arm can hold the picture surface tight against the message form and yet an arrangement which can be quickly released upon being moved in a counter-clockwise direction (looking at Fig. 3) about 32 as a pivot and thus quickly release the picture from the message form. It is to be noted that Fig. 4 is 80 shown in opposite relationship to the showing of Fig. 2 and that if Fig. 2 is turned end for end so that the light directed from the lens 4 can be assumed to direct itself toward the bottom of the page instead of toward the top of the page, as shown, the analogy between Figs. 2 and 4 will be at once apparent and it will be seen that the photocell to which the reflected light from the reflecting system 21 is directed will be placed at the left end of the light tube 2 of Fig. 4.

Preferably in carrying out the invention, means are provided for adjusting the "phase" of the receiving device so that should the streak of light referred to in the last paragraph not fall in the correct plane on the message form, adjustments may be made. This may be effected by rotatably mounting the driving means, for example, a synchronous motor, in trunnions or the like and rotating the whole machine by means of suitable gearing, thereby advancing or retarding the armature. This adjustment may be effected either by hand or automatically.

Preferably the message form or receiving surface does not occupy the whole cylindrical circumference of the message carrier (tube 7 in the figures), but embraces only an arc thereof. If desired a plurality of such message forms may be employed so that between them they occupy substantially the whole cylindrical circumference, and a corresponding plurality of machines be provided, the said machines being mechanically or electrically geared together and the arrangement being such that the several spots of light traverse their respective arcs successively, thereby utilizing the complete revolution. In this way a multi-way system having two or more independent spots of light may be obtained.

In the modification shown in Figures 3 and 4, 12 is a driving motor which is mounted upon a pedestal 13 and whose carcase may be rotated by means of a handle 14 driving a 130

worm and worm wheel 15. Drive is transmitted through the worm and worm wheel 16 to a shaft 17 having mounted thereon worms 18 and 19, the former of which 5 rotates a screwed shaft 18^a, serving progressively to traverse the form 6 while the latter rotates the tube 2 in which are mounted lenses 4 and 8, and optical devices 20 and 21 which serve the same purposes as the parts 10 3 and 9 of the arrangement shown in Figures 1 and 2.

Having described our invention, we are entitled to all modifications that fall fairly within its scope as defined by the following 15 claims, wherein we claim:

1. In a picture transmission system, a stationary source of light, a message form for supporting the picture to be transmitted, optical means for projecting the light from 20 said source to a point on said supported picture, means for mounting said optical means within said message form, means for causing said projected light to traverse the entire message form, and means for collecting 25 light reflected from said picture.

2. In a picture transmission apparatus, a message form adapted to support a picture, a stationary source of light, means for directing said light within said message form, 30 optical means for projecting a point of said light upon said message form, said means comprising a reflecting prism and a lens, a second lens concentric with said first named lens, said second lens being adapted to direct reflected light from said message form, and electrical means controlled by said reflected light for varying the strength of an electric current in proportion to the pigmentation of the picture upon said message 35 form.

3. In a picture transmission apparatus, a support adapted to mount a message to be transmitted, a stationary source of light, means for directing said light within said support and longitudinally thereto, means for diverting said light through an angle and projecting it upon the message mounted upon said support, means for collecting the light reflected from said message, and means 45 for diverting said reflected light in the path substantially in a straight line with the light issuing from said source.

4. The system claimed in claim 3 wherein a photo-electric cell is positioned in the path 50 of said diverted reflected light, said photo-electric cell being adapted to produce variations in an electric current in a circuit associated therewith in accordance with the light and shade of the message mounted upon said support.

5. The system claimed in claim 3 wherein means is provided for rotating said light projecting and diverting means, whereby the entire message upon said support is exposed to light from said source.

6. In a picture transmission system, a stationary source of light, a message form for supporting a picture to be transmitted, optical means for projecting the light from said source to a point on said supported picture, means for rotating said optical means within said message form, means for causing said projected light to traverse the entire message form, means for collecting light reflected from said picture and means associated with said collecting means for increasing the amount of reflected light from said picture surface reaching said collecting means.

7. In a picture transmission system, a stationary source of light, a message form for supporting a picture to be transmitted, optical means carried within said message form for projecting light against said message form, means for causing said projected light to trace successive paths transverse of said message form, means for advancing said message form with respect to said projected light whereby each successive path of projected light covers a different portion of 85 the picture carried by said message form and means for collecting the light reflected from said message form.

8. A picture transmitting apparatus including a member adapted to support a picture bearing sheet, a rotatable member, means mounted on said member for projecting light upon said sheet, and means for receiving and directing the light reflected from said sheet along a predetermined path.

9. A picture transmitting apparatus including means for supporting a picture bearing sheet, a rotatable member, a lens mounted on said member for projecting light upon said sheet and a lens mounted on said member for receiving the light reflected from said sheet.

10. A picture transmitting apparatus including means for supporting a picture bearing sheet, a rotatable member, a lens mounted on said member for projecting light upon said sheet, a lens mounted on said member for receiving the light reflected from said sheet, and means mounted on said member for changing the direction of the light reflected through said lens.

11. A picture transmitting apparatus including a stationary support, a hollow shaft, means mounted on said shaft for projecting light toward said support and for receiving the light reflected away from said support and means arranged to direct said reflected light through said hollow shaft.

12. A picture transmitting apparatus including a support, a hollow rotatable shaft, a lens mounted on said shaft for projecting light toward said support, a lens on said shaft for receiving the light reflected away from said support, and a prism arranged to 130

direct said reflected light along the axis of said shaft.

13. A picture transmitting apparatus including a support, a rotatable shaft, a lens mounted on said shaft for projecting light toward said support, a microscope on said shaft for receiving the light reflected away from said support, a prism arranged to direct said reflected light along the axis of said shaft, and means for moving a picture bearing sheet past said support.

14. A picture transmitting apparatus including a support for a picture bearing sheet, a rotatable member, means mounted on said member for projecting light toward said picture bearing sheet and for receiving the light reflected away from said sheet, and means for moving said sheet.
